(57) CLAIM

The ornamental design for pants, as shown and described.

DESCRIPTION

This application is a continuation-in-part of U.S. patent application Ser. No. 16/028,653 filed on Jul. 6, 2018. The above identified patent application is herein incorporated by reference in its entirety to provide continuity of disclosure.

FIG. 1 is a perspective view of the pants;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The shade lines in the figures show contour and not surface ornamentation.

The broken lines shown in the figures depict portions of the pants which form no part of the claimed design.

1 Claim, 4 Drawing Sheets
